FIG. 1.

FIG.3.

FIG. 2.

Inventor

334 *J. M. P. Farbey*

UNITED STATES PATENT OFFICE.

JOHN P. TARBOX, OF GARDEN CITY, NEW YORK, ASSIGNOR TO TARBOX SAFETY AIRCRAFT COMPANY, A CORPORATION OF DELAWARE.

TRANSVERSE AXIS AILERON.

1,423,166.

Specification of Letters Patent. Patented July 18, 1922.

Application filed June 20, 1918. Serial No. 240,981.

To all whom it may concern:

Be it known that I, JOHN P. TARBOX, a citizen of the United States, residing at Garden City, in the county of Nassau and State of New York, have invented certain new and useful Improvements in Transverse Axis Ailerons, of which the following is a specification.

The aileron of this invention is of the transverse axis type. As disclosed it is extended laterally from the lateral extremity of the aeroplane wing. It may or may not be of the same aerofoil section. As disclosed it is of the same section. In one case I disclose a pair of ailerons and in the other case a single aileron, in each case as applied to a biplane. Application may also be made to a monoplane or multiplane.

The form disclosed is especially suited for realization in the automatic balancing systems such as is disclosed in my pending application, Serial No. 240,983. These systems are characterized by a differential action between the ailerons on opposite sides of the machine in response to the air pressure. With this in view, the aileron is mounted on a transverse axis lying in advance of the foremost point of normal travel of the center of pressure of the aerofoil section employed. The axis is fixed and forms a part of the rigid framework to the body of the aeroplane, the aileron enclosing it and yet being pivotally mounted thereon. The whole organization is such that a maximum efficiency and effectiveness of the aileron is secured co-incidentally with the maximum strength of structure and minimum resistance.

Of the drawings:

Fig. 1 shows the single aileron construction;

Fig. 2 shows double aileron construction;

Fig. 3 is a detail of the outboard axis support.

The biplane wings designated 10 in each case are in the instance of Fig. 1 not co-extensive, the upper wing being terminated short of the lower wing. The aileron 11 not only fills out the length for the upper wing but extends beyond the lower wing to pro-

duce what is commonly known as an overhang by its overhanging tip 12. At the terminus of the upper wing, the biplane wings are spaced apart by the usual interwing struts 13. The aileron axis 14 is connected at its inner end 15 to the interior structure of the upper wing and extends in the case illustrated from a point within its transverse section laterally parallel to the lower wing. The axis 14 may not in all cases be parallel since at times the lower wing has a marked angle to the upper wing. Still further the axis itself may be inclined with respect to the upper wing. The end 15 is preferably connected to strong compression ribs (of the usual form and not shown) or equivalent members between the wing beams and therefore between the interwing struts 13, yet in advance of the foremost point of normal forward travel of the center of pressure. The outer end of the axis 14 is supported fixedly at the upper end by a pair of converging struts 16 founded at their lower ends on the front and rear wing beams of the lower wing. A detail of this connection is shown in Fig. 3. As shown, a split clamp 17 connects struts 16 with axis 14. Diagonally extending lift and load wires of the usual form (designated 18) connect the clamp 17 respectively with the lower ends of struts 16 while similar wires connect respective lower ends of the struts 16 with the corresponding upper ends of the struts 13. The whole constitutes a rigid framework and the members 13 and 14 a pyramidal structure with its base founded on the wings.

The aileron 11 is supported upon axis 14 through interior bearings 19 within its body and preferably of the ball or frictionless type, there being along axis 14 as many of these bearings as is desired. Four of them are shown. The clamp 17 is located in an aperture 20 in the body. This aperture is shown as extending through the aileron but may be a mere recess opening on the under side only. The aileron is operable through cables 21 connecting with points in advance and to the rear of the axis 14 and in turn connected to cooperating ailerons or appropriate actuating devices. It will be ob-

100

served that there are no more exposed wires or struts in this construction than there are in any other biplane of similar wing arrangement and having the usual Pratt trussing. At the same time and incidentally an efficacious mounting for the aileron is secured permitting great freedom and ease of movement of the aileron surface and eliminating all liability of jamming. The wiring 10 18 may be omitted if desired, the pyramidal form of the strut arrangement giving ample stiffness.

The process of assembly is as simple as can be desired. The axis 14 is put into place 15 (the end 15 is fitted into a provided socket or connected with certain interior metallic fittings in the wing) and bolted fast. The struts 16 are erected on the outer end of the lower wing and the wires 18 connected 20 loosely in place. Then before the axis 14 is set in the clamp 17, the aileron 11 is slipped onto the axis 14 by simply pushing its bearings over the axis rod or shaft. Its inner end is spaced by a suitable clearance from 25 the upper wing. Then the outer end of the axis is lowered into the clamp 17 and the clamp bolted in place as indicated in Fig. 3, whereupon the wires 18 may be appropriately tightened.

30 The double aileron construction of Fig. 2 is similar. Instead, however, of a dual strut 16 there is a single branched outer strut 22 only, the opposite ends of which 23 and 24 are each connected rigidly with an axis 14 35 in a manner similar to the upper end of strut 16. The wires 18 connect the upper and lower ends 23 and 24 respectively with the lower and upper ends of struts 13. By reason of the fact that strut 22 lies in a 40 transverse plane passing intermediate struts 13 and the points of attachment of wires 18 thereto (or to the wings in their vicinity) there is provided a triangulated or 45 pyramided structure which results again in an absolutely rigid structure. The rigidity of the structure may be increased if desired by spreading the inner ends of the wires 18 still farther from the axes 14, carrying them toward or to the leading and trailing edges 50 of the wings respectively, but this will not ordinarily be necessary. The ailerons are in this case operated by cables 25 connected respectively with the upper and lower ailerons and crossed to effect conjoint operation of 55 the ailerons through compression strut 26.

Obviously the structural details of my invention may be varied to a considerable extent without departing from the generic spirit of my invention. In any such case I 60 desire to have it understood that these constructions, as well as those disclosed, are included within the purview of the appended claims.

What is claimed is:

65 1. In an aeroplane, upper and lower sup-

porting surfaces, an aileron in lateral extension of one of said surfaces, and a supporting structure therefor comprising a vertical strut spaced laterally of the end of one of the supporting surfaces and extending between the aileron and the surface vertically adjacent, laterally extending beams extending from the upper and lower ends of the main supporting surface to the upper and lower ends of the strut respectively, front 70 and rear interwing struts associated with the main supporting surfaces, and cross wiring between the upper and lower ends of said latter struts and the lower and upper ends of the first-named strut. 75

2. In a biplane, an aileron in lateral extension of one of the wings, an aileron bearing member projecting laterally of one of said wings, a vertically extending strut interconnecting said member with a projection 80 extending laterally from the wing surface vertically next adjacent, interwing struts for the main supporting surfaces, and cross wiring connecting the upper and lower ends of said latter struts respectively with the lower 85 and upper ends of the said vertical strut. 90

3. In a biplane, ailerons in lateral extension of each of the wings thereof, fixed interwing struts between the main supporting surfaces, aileron axis supporting members 95 extending laterally from the main surfaces and rigidly connected therewith at points intermediate the front and rear end struts, a vertical strut rigidly interconnecting the said axis supporting members, and cross wiring between the upper and lower ends of said interwing struts and the lower and upper ends of said axis connecting strut respectively. 100

4. In a biplane, interwing struts, an aileron 105 in lateral extension of one of the wings, and a framework supporting said aileron oscillatably and comprising a laterally extending frame member emanating from the end of one wing at a point intermediate the front 110 and rear interwing struts, a vertical strut rigidly connecting an outer portion of said frame member and a member connected to the wing structure next vertically adjacent, and cross wiring between the upper and lower ends of said interwing struts and the lower and upper ends of said vertical strut respectively. 115

5. In a biplane, an aileron in lateral extension of one of the wings, an aileron bearing member projecting laterally of one of said wings, a vertically extending strut structure interconnecting said member with a projection extending laterally from the wing surface vertically next adjacent, interwing struts for the main supporting surfaces, and truss members connecting the upper ends of said interwing struts with the lower end of said strut structure. 120

6. In a biplane, an aileron in lateral ex- 125

tension of one of the wings, an aileron bearing member projecting laterally of one of said wings, a vertically extending strut structure interconnecting said member with

5 a projection extending laterally from the wing surface vertically next adjacent, interwing struts for the main supporting sur-

faces, a cross wiring connecting the upper and lower ends of said interwing struts respectively with the lower and upper ends of 10 said vertical strut structure.

In testimony whereof I hereunto affix my signature.

JOHN P. TARBOX.
